UNITED STATES PATENT OFFICE

154,699

DESIGN FOR A RADIATION METER

Everett W. Molloy, Wilmar, Calif., assignor to
 National Technical Laboratories, South Pasadena, Calif., a corporation of California

Application January 8, 1949, Serial No. 131

Term of patent 14 years

(Cl. D52—1)

To all whom it may concern:

Be it known that I, Everett W. Molloy, a citizen of the United States, residing at Wilmar, county of Los Angeles, State of California, have invented a new, original, and ornamental Design for a Radiation Meter, of which the following is a specification, reference being had to the accompanying drawing, forming part thereof, in which:

Figure 1 is a perspective view of a radiation meter embodying my new design, showing a handle of the meter in a retracted position and showing a probe of the meter in a demounted position;

Figure 2 is a rear view of the radiation meter, showing the handle in its retracted position;

Figure 3 is a plan view of the radiation meter, showing the handle in an extended position and showing the probe in mounted position;

Figure 4 is a front view of the radiation meter, showing the handle in its extended position and the probe in its mounted position; and,

Figure 5 is an end view of the radiation meter

embodying my new design, showing the handle in its retracted position and the probe in its mounted position.

I claim:

The ornamental design for a radiation meter, substantially as shown.

EVERETT W. MOLLOY.
